TEMPORARY HOLDER FOR THE KEYBOARD CAMS OF A LINOTYPE MACHINE OR THE LIKE

Robert P. McElroy, Queens Village, N. Y.

Application June 1, 1956, Serial No. 588,870

7 Claims. (Cl. 51—217)

The subject of this invention is a novel and valuable device for use as a temporary holder of a large plurality of certain operating units of a Linotype, Intertype or like machine, to facilitate quick and easy cleaning and oiling of said units; said units being all alike, and, in the case of the Linotype machine, there being 91 of said units.

Said units are the so-called keyboard cams; each actually consisting of a cam rotatably mounted in a slot through an elongate carrier called the cam yoke. Beyond the opposite ends of said slot, said carrier terminally includes a pair of integral reduced extensions each in the nature of a plate in line with said slot. Such a unit will hereinbelow be called a cam and yoke unit.

As is well known, it is necessary at comparatively frequent intervals to remove all the cam and yoke units from a Linotype machine, in order to remove rust, dirt and other undesirable additions to or accumulations on each cam and yoke unit, and to oil each such unit. In the case of each unit the removal of the rust, dirt, &c., has to be done at each of the opposite side faces of the terminal, plate like extensions of each of the yokes of the 91 units; and in the case of each unit, the oiling thereof must be effected at both the opposite sides of each of the yokes in a way to supply the oil properly relative to the pivot pin by way of which the cam is rotatably mounted in the slot of the yoke.

Also, as is well known, a Linotype machine is so constructed that relatively very little time is required to remove all the 91 units, preparatory to cleaning and oiling them, and to remount them in the machine after cleaning and oiling them, compared to the time required to clean and oil them when the cleaning and oiling are in the usual way performed in regard to each unit individually, one after the other, incidental to handling of each unit as a single separately directly manually grasped entity. This cleaning and oiling of each unit separately and during finger manipulation thereof is ordinarily done by the machinist in charge of maintaining the Linotype machine always in good operating condition, and consumes many hours of his time. But the disadvantage last referred to is not the greatest, because between the removal of the 91 units and their remounting in the machine after having been cleaned and oiled, the Linotype machine is of course out of commission.

According to the present invention, a temporary holder for a large plurality of the cam and yoke units is provided as aforesaid, with said holder incorporating a plurality of relatively adjustable members so constructed and arranged that, in one setting of one of said members relative to the other, a plurality of lines of said cam and yoke units are all held with one of the two opposite faces of each of the said terminal plate-like extensions of each yoke exposed and positioned for easy sweep over all of said faces of an instrumentality (as a hand-held wood block faced with a light emery cloth) for cleaning all of said faces by said sweep. In the said setting of one of the holder members relative to the other, also, said

plurality of lines of said cam and yoke units are all held with the other of the two opposite faces of each of the said terminal plate-like extensions of each yoke exposed and positioned for easy sweep over all of said faces of said instrumentality for cleaning all of said faces by said sweep. In this setting of said holder, further, each yoke in each of said plurality of lines thereof is exposed at one side of the yoke along a central length thereof whereat its cam and the pivot pin for the latter are located, to facilitate easy oiling at that side of each yoke.

In a setting of said holder different from that described in the preceding paragraph, all the cam and yoke units in said plurality of lines thereof are still held securely in place, yet in such way that now each yoke in said plurality of lines thereof is exposed at the other side of each yoke along the central length of the yoke whereat its cam and the pivot pin for the latter are located, to facilitate easy oiling at that side of the yoke.

Various other features, objects and advantages of the invention will be hereinafter referred to or become apparent during the course of the following description of a now preferred embodiment of the invention as illustratively shown in the accompanying drawings, of which—

Fig. 1 is a side elevational view of one of the like 91 cam and yoke units of a Linotype machine, drawn approximately to full size;

Fig. 2 is a top plan view thereof;

Fig. 3 is a top plan view of a holder for temporary use pursuant to the invention in holding a large plurality of said units for the quick cleaning and oiling thereof;

Fig. 4 is a view similar to Fig. 3, but showing one of the aforesaid plurality of adjustable members of the holder, the last-named member being hereinafter called the lesser or adjustable frame, after removal from the other of said members, the latter being hereinafter called the main frame.

Fig. 5 shows the parts illustrated in Fig. 3 as they would be seen were the lesser or adjustable frame of Fig. 4 removed from the holder of Fig. 3; except that in the case of one intended location for a cam and yoke unit a showing of said unit has been omitted, to illustrate the nature of the seating formations provided for each of said units;

Fig. 6 is an enlarged fragmentary detail view, this being a section taken on the line 6—6 of Fig. 3;

Fig. 7 is a view similar to Fig. 6, but a section taken on the line 7—7 of Fig. 4; and

Fig. 8 is a view similar to Fig. 3, but with now the lesser frame repositioned on the main frame thereby to give the holder its different setting hereinabove second mentioned, that is, its setting different from that shown in Fig. 3.

Referring now to the drawings more in detail, each cam and yoke unit shown is as a whole designated 15.

As indicated in Figs. 3, 5 and 8, although only fifteen of the units 15 are seen as mounted in the holder, the latter, which as a whole is marked 16, may be made of a length such as to adapt the holder for securing therein any desired total of the units 15. A now preferred capacity for the holder, at any one use thereof for cleaning and oiling a plurality of the units 15, is such that 45 units are held at one and the same time, fifteen units in each of three rows thereof.

Each unit 15, as best shown in Figs. 1 and 2 and as is well known, comprises a cam 17 in an elongate yoke 18 having lengthwise thereof a slot 19; the arrangement being such that said cam, mounted on a pivot pin 20 extending across said slot, is loosely rotatively suspended in the yoke 18. Also as is well known and as shown in Fig. 2, the cam 17 is comprised of two like spaced plates locked against movement one relative to the other by the

pivot pin 20 and another pin 21 secured at opposite ends to each of said plates. Further as is well known, a Linotype machine has its cam and yoke units arranged in rows with all the units of each row so placed that one unit in a row is closely alongside another in the same row and all the cams are vertical. As is further well known, a Linotype keyboard has 91 keys each at the outer end of a keyboard lever, in combination with an arrangement such that on depression of any one of said keys its lever moves to cause a rocking of a trigger thereabove normally holding a yoke 18 of the associated unit 15, said yoke hung from a suitable pivot element by aid of a hook bill 22 on the yoke, from dropping at its right hand end as seen in Fig. 1; said dropping of said yoke end moving the pin 21 from detention by a depending interceptor member, and in consequence freeing the cam to rotate by its own weight about its pivot pin in a clockwise direction as seen in Fig. 1—thereby, in turn, to bring a serrated edge portion of the cam into engagement with a rubber roller therebelow and continuously rotating in a direction such that by its engagement with the said edge portion of the cam the yoke is forced to function as an upwardly thrusting lever to cause rise of a rod to release the appropriate matrix of the Linotype machine.

As most clearly shown in Figs. 1 and 2, the hook bill 22, a depending one, is part of a hook formation of a blade-like reduced front end extension 23 of the main body of the yoke 18, and at the rear end of said yoke's main body there is a blade-like reduced extension 24. The opposite faces of both said extensions, or blades as they will hereinbelow be called, are parallel and plane, and must frequently be cleaned of rust, dirt and other undesirable accumulations.

The holder, desirably made of aluminum or the like for lightness of weight, and as a whole as aforesaid designated 16, incorporates a main frame, this main frame as a whole designated 25, comprising two laterally extending end pieces 26 and 27 joined by three strips or bars 28, 29 and 30. The end piece 26 is shown undercut along its length across the main frame (Fig. 6) to provide a groove 31 for receiving in slide relation thereto a tongue 32 formed on one end of the lesser or adjustable frame of the holder, which latter frame is as a whole marked 33. Said frame 33, as best seen from Fig. 4, also comprises two end pieces, these respectively marked 34 and 35, and joined by three strips or bars 36, 37 and 38. As will be noted it is the end piece 34 which carries the tongue 32.

The bars 28, 29 and 30 of the main frame 25, all said bars of the same width, are uniformly spaced as shown, as are the bars 36, 37 and 38 of the lesser frame 33, although as shown all said bars 36, 37 and 38, while of the same width, are of less width than the bars 28, 29 and 30.

A means is provided for readily temporarily locking the holder 16 in either of its two settings; one of said settings being that shown in Fig. 3, wherein the bars 36, 37 and 38 are positioned so that their center lines are in registry with the center lines of the bars 28, 29 and 30, and the other of said settings being that shown in Fig. 8, for exposing portions of the yokes 18 adjacent to the pivot pins 20 for the cams 17 of all the 45 units 15 in the frame 16. Said means is shown as in part comprised of the tongue and groove couple 32—31 (see especially Figs. 6 and 8), and in part comprised of a spring bolt of conventional type set in a suitable sleeve or tube tight in a hole of suitable diameter extending across the end piece 27 of the main frame 25. At its left hand end as seen in Figs. 3, 5 and 8 said bolt is shaped to provide a convenient handle 40 whereby against the tension of the bolt spring said handle may be manually pulled to retract into the end piece 27 the opposite end of the bolt projected normally as shown at 41 in Fig. 5. For receiving said end 41 of the bolt, when pull on the handle 40 is released, two cylindrical recesses as at 42 and 43 in Figs. 4 and 7 are provided in the end piece 35 of the lesser frame 33.

These recesses are so located that with the holder 16 in the setting shown in Fig. 3, the end 41 of the bolt is in the recess 42, and with said holder in the setting shown in Fig. 8, the end 41 of the bolt is in the recess 43.

That one of the 45 seating formations (one for each of the 45 cam and yoke units 15 to be placed at any one time in the holder 16 in the embodiment thereof illustrated) hereinabove referred to in the brief description of Fig. 5, is in that view shown as comprising a cylindrical hole 44 extending all the way through the bar 29 of the main frame 26 and as also comprising a pair of channels 45 and 46 in the upper portion of said bar 29, these channels aligned one with the other, and extending in a direction transverse to the length of said bar and across the top of the hole 44 and offset to one side of the center of cylindricity of said hole. The said channels 44 and 45 are of identical width and depth; the yoke 18 of a unit 15 along the length of said yoke between its blades 23 and 24 is (disregarding its slot 19) of square cross-section; and said channels cross-sectionally, and said yoke cross-sectionally, are so dimensioned that one end of the yoke fits in the channel 45 so as somewhat to project above the top of said channel as shown in Fig. 6. Thus, with the two ends of the yoke dropped into the channels 44 and 45, so that both of said yoke ends project upwardly to an equal extent above the top of the bar 29, it is possible to construct the holder 16 so that the bar 37, when arranged, and then locked as already explained by locking the lesser frame 33 to the main frame 25, as shown in Fig. 3 or as shown in Fig. 8, may be relied on to press down hard and tight against the upwardly projected portions of the yokes of all the cam and yoke units 15 in their seating formations along the entire length of the bar 37, with, at the same time, the bar 36 bearing down hard and tight against the upwardly projected portions of the yokes of all the units 15 in their seating formations along the entire length of the bar 28, and also with, at the same time, the bar 38 bearing down hard and tight against the upwardly projected portions of the yokes of all the units 15 in their seating formations along the entire length of the bar 30.

It has already been mentioned that in a Linotype machine there is a total of 91 cam and yoke units 15. Also, the embodiment of the invention as illustrated in the drawings has been hereinabove stated to be preferably one having a capacity for holding 45 of said units at any one use of the holder in connection with the cleaning and oiling of a large plurality of the units. Thus, in the case of the holder 16, made to have a capacity in accordance with the just stated preference, two such uses of the holder would take care of 90 of the 91 units 15, with one over, this to be cleaned and oiled while held directly in the hand as in the present practice relative to each of the 91 units. Or the holder could be so made as to have a main frame, as the main frame 25, carry 46 instead of 45 of the seat formations 44—46, so that at one use of the holder a total of 45 units would be taken care of and at the next following use of the holder a total of 46 units would be taken care of.

Operation

(1) With main frame 25 resting on a suitable support so that, as in Figs. 3 and 6 for example, its end pieces 26 and 27 are above its strips or bars 28, 29 and 30, the lesser frame 33 is detached and removed; by first pulling on the handle end 40 of the spring bolt to free the opposite end 41 (Fig. 5) of said bolt from its engagement with that one of the recesses 42 and 43 (Figs. 4 and 7) lengthwise into which said bolt end may then be extended, then by lifting the end of said lesser frame at the end piece 35 thereof high enough to permit said end piece 35 to clear the end piece 27 of the main frame 25 sufficiently to allow the lesser frame to be pulled to the left to an extent fully to disengage the two frames at the

right hand end of the holder 16, that is, so as to slide the tongue 32 laterally thereof out of the groove 31.

(2) With now the lesser frame 33 removed from the main frame 25, 45 of the units 15 are placed as already described and as shown in Fig. 5 relative to said frame 25, each such unit in a seating formation like that shown in this view at 44—46.

(3) After this, the lesser frame 33 is restored to the holder so as to be disposed relative to the main frame 25 as shown in Fig. 3, and so as to be thus secured in place, by first sliding the tongue 32 laterally thereof into the groove 31 so as to position said tongue and groove in the relation shown in Fig. 3, and next proceeding as follows: Manual pull is exerted on the handle 40 of the spring bolt to retract its opposite end 41 wholly into the end piece 27 of the main frame 25, next while holding said bolt so retracted at its said end 41 the lesser frame 33 is lowered at its end piece 35 so as to bring the recess 42 in said end piece opposite said bolt end 41, and next said bolt handle is released.

(4) When, as will shortly below be explained, the lesser frame 33 is to be repositioned on the main frame 25 as shown in Fig. 8, first the handle 40 of the spring bolt is pulled to release the lock between the two frames at the left hand end of the holder 16, then the lesser frame is lifted at its left hand end sufficiently to permit shift of the right hand end of said frame to dispose its tongue 32 in the groove 31 at the right hand end of the main frame 25 as shown in Fig. 8, and then the operations described in the last sentence of the immediately preceding paragraph are performed as therein described except that here it is the recess 43 (Fig. 4) into which is sent the end 41 (Fig. 5) of the spring bolt on release of the bolt handle 40.

Following completion of the steps (1), (2) and (3) of the procedures outlined above, all the blades 23 and 24 of all 45 of the units 15 in the holder 16, at the faces of said blades seen in Fig. 3, are cleaned quickly and easily by four series of manually performed sweepings thereover by a suitable instrumentality, as a light emery cloth constituting a facing carried by a hand tool as aforesaid.

One of said sweepings is to clean, as to all the units 15 in the row or line thereof held in place by the bar 36 of the lesser frame 33, the faces of the plates 24 seen in Fig. 3 and shown in that view as carried at the upper ends of said units.

Another of said sweepings is to clean, as to all the units in the row thereof just mentioned, the faces of the plates 23 of said units seen in Fig. 3 and shown in that view as carried at the lower ends of said units, and also, as to all the units in the row or line thereof held in place by the bar 37 of the lesser frame, the faces of the plates 24 seen in Fig. 3 and shown in that view as carried at the upper ends of the last-named row or line of units 15.

Another of said sweepings is to clean, as to all the units in the row of units held in place by said bar 37, the faces of the plates 23 seen in Fig. 3 and shown in that view as carried at the lower ends of the units of said row, and also, as to all the units in the row or line thereof held in place by the bar 38 of the lesser frame, the faces of the plates 24 seen in Fig. 3 and shown in that view as carried at the upper ends of the last-named row or line of units 15.

Another of said sweepings is to clean, as to all the units in the row of units held in place by the bar 38, the faces of the plates 23 seen in Fig. 3 and shown in that view as carried at the lower ends of said units.

In the case of each of said sweepings, merely two or three quickly performed light strokes of an instrumentality of the kind above referred to, each such stroke of a length just short of the spacing between the end pieces 34 and 25 of the lesser frame 33, has been found to be ideal for properly cleaning the faces of all the plates 23

and 24 of all the 45 units 15 in the holder, at the faces of said plates seen in Fig. 3.

Following completion of the four sweepings as just above described, the holder 16 as shown in Fig. 3 is turned upside down, and then four additional sweepings, these respectively corresponding to the four sweepings first performed, are done, for quick and easy cleaning, as to all 45 of the units 15, of the faces of their blades 23 and 24 opposite to the faces thereof seen in Fig. 3.

Following completion of the said four additional sweepings, the holder 16 is up-ended, with its end at the right in Fig. 3 lowermost, and now the required oiling of the pivot pins 20 of all the 45 units 15 is commenced. During this oiling, use may conveniently be made of a so-called oil pen. With the holder 16 set as to its two frames 25 and 33 as shown in Fig. 3, and with the holder up-ended as just mentioned, the first oiling is done relative to the portions of said pivot pins adjacent to the ends of said pins opposite to the ends thereof seen in Fig. 3; this being possible because each seating formation 44 (Fig. 5) for the cam of a unit 15 is a cylindrical hole going all the way through its carrying bar 28, 29 or 30 of the main frame 25. Since, as will be noted particularly from Fig. 1, the location of a pivot pin 20 is closer to what in Fig. 25 is the left side of a yoke 18 than to the opposite side of said yoke, it is highly desirable to have the yokes of the units 15 so placed in the holder 16 that, when the latter is up-ended to facilitate oiling as above, it will be, in the case of each of the yokes, the side of the yoke which is closer to its pivot pin 20 which will be uppermost; and that, it will be observed, is the advantageous situation provided for by the manner in which all the seating formations 44—46 are placed relative to that end of the holder 16 which when lowermost (i. e., which does not carry the handle 40 of the spring bolt) can be squarely rested on a suitable flat support. Then, as an oil drop is applied to one unit after another, this oil may be sent downward into the space between a side wall of the slot 19 and the adjacent face of the cam 17 of a unit 15 in a manner most effective to reach properly the adjacent end portion of the pivot pin 20 of said unit.

Following completion of the oiling step described in the immediately preceding paragraph, and with the holder 16 now laid flat and with the lesser frame 33 uppermost as in Fig. 3, the hereinabove listed step (4) of the stated procedure is carried out, thereby to change the setting of the holder 16 from that shown in Fig. 3 to that shown in Fig. 8.

Now, it will be noted, all the pivot pins 20 of all the units 15 and the adjacent portions of the yokes 18 of said units previously covered by the bars 36, 37 and 38 of the lesser frame 33 will be sufficiently uncovered to permit, following up-ending of the holder 16 as before, the only other oiling required to be done relative to the pivot pins 18 at the portions of said pins opposite to the portions thereof previously oiled; which second oiling can easily be effected in the same manner and with the same speed and efficiency as described in the second preceding paragraph hereof.

A feature of the invention, moreover, resides in the fact that, despite the shifting of the bars 36, 37 and 38 of the lesser frame 33 laterally of the bars 28, 29 and 30 of the main frame 25, there remains enough overlap of the narrower bars 36, 37 and 38 relative to the wider bars 28, 29 and 30 to set up and maintain a good tight hold on all the units 15 with the holder 16 in the setting thereof shown in Fig. 8. In this connection, attention is called again to Fig. 6, and to the statement hereinabove made that the bars 36, 37 and 38 are so included in the holder combination as to bear down hard on all the units 15 therebelow. Absolutely to insure this result, the yokes of said units are so seated in a bar 28, 29 or 30, as the case may be, as to project upwardly as shown in Fig. 6 in the case of the yoke 18 there seen, above the said bars 28, 29 and 30.

To permit quick removal from the holder 16 of all the 45 units 15 after the latter have been cleaned and oiled while in the holder as above described, all that is required, as will now be understood, is to perform step (1) of the hereinabove stated procedure to be carried out; and, after removal of said units (and after, if then desired, placing in the main frame 25 another large plurality of other units 15), all that is required, for restoration of the holder 16 to its setting as shown in Fig. 3, is to perform step (3) of said procedure.

The present invention may be used not only in connection with the cam and yoke units of a Linotype machine but also in the manner already described in connection with the cam and yoke units of an Intertype machine, by suitably modifying where and if necessary the seating formations 44-46. As is well known, said units of an Intertype machine, like the units 15 of a Linotype machine, incorporate cam pivot pins needing frequently to be oiled at the opposite end portions thereof and also incorporate yokes carrying reduced terminal extensions in the nature of blades having opposite faces needing frequently to be cleaned of rust, dirt and other undesirable accumulations. Whenever in the appended claims a cam and yoke device is referred to, there is meant a cam and yoke unit 15 of a Linotype machine, whether as now made or later somewhat modified, and also a similar unit of an Intertype machine or the like.

While a now preferred embodiment of the holder of the present invention has been described with great particularity of detail, it is to be understood that this has been done, of course, not for purposes of limitation, but to illustrate and fully explain the various important capabilities of the invention. As will be understood, variations and modifications are possible, as to materials used and dimensions employed, and parts of the improvements may be used without others. The scope of protection contemplated is to be taken primarily if not entirely from the appended claims.

I claim:

1. A holder for a plurality of cam and yoke units, said holder comprising an elongate main frame incorporating a plurality of longitudinally extending bars laterally spaced one from another, each bar having spaced along its length a plurality of seating formations each so shaped as to have fittable therein one of said units, an elongate lesser frame also incorporating a plurality of longitudinally extending bars laterally spaced one from another, and means partially carried by both frames and adjustable to insure placement of the lesser frame in one predetermined position relative to the main frame thereby to give the holder one setting and also otherwise adjustable to insure placement of the lesser frame in another predetermined position relative to the main frame thereby to give the holder another setting, said bars being so placed in their frames and being of such widths that in the first named setting of the holder the bars of the lesser

frame cover the central portions of said units and in the second named setting of the holder the bars of the lesser frame uncover the central portions of the units but cover other portions of the latter, which last named unit portions although offset from the unit centers are sufficiently close to said centers to securely maintain all the units in their said seating formations in the bars on the main frame.

2. A holder as in claim 1, wherein each of said formations includes a cylindrical hole going all the way through the bar carrying that formation, each of said formations also including a pair of aligned channels extending laterally across the upper side of said bar, said channels at their inner ends opening into said hole.

15 3. A holder as in claim 1, wherein each of said formations includes a cylindrical hole going all the way through the bar carrying that formation, each of said formations also including a pair of aligned channels extending laterally across the upper side of said bar, said channels at their inner ends opening into said hole, said channels arranged along a line offset from the center of cylindricity of said hole.

20 4. A holder as in claim 1, wherein said means includes a component at one end of the holder comprising a tongue and groove couple one member of which couple is carried by and extended across the main frame and the other member of which is carried by and extended across the lesser frame.

25 5. A holder as in claim 1, wherein said means includes a component at one end of the holder comprising a tongue and groove couple one member of which couple is carried by and extended across the main frame and the other member of which is carried by and extended across the lesser frame, and wherein the direction of offset of

30 35 said offset line is toward the last-named end of the holder.

6. A holder as in claim 1, wherein each of said formations includes a cylindrical hole going all the way through the bar carrying that formation, each of said formations also including a pair of aligned channels extending laterally across the upper side of said bar, said channels at their inner ends opening into said hole, each bar of the main frame being wider than a bar of the lesser frame.

35 40 7. A holder as in claim 1, wherein each of said formations includes a cylindrical hole going all the way through the bar carrying that formation, each of said formations also including a pair of aligned channels extending laterally across the upper side of said bar, said channels at their inner ends opening into said hole, each bar of the main frame being wider than a bar of the lesser frame, the bars of the main frame being of equal width and the bars of the lesser frame also being of equal width, the main frame having at least three bars equally spaced one from another and the lesser frame having at least three bars equally spaced one from another.
